(No Model.)

J. CHRISTMAN.

AUTOMATIC FEED WATER REGULATOR FOR STEAM BOILERS.

No. 269,512.

Patented Dec. 26, 1882.

UNITED STATES PATENT OFFICE.

JOHN CHRISTMAN, OF SYRACUSE, NEW YORK.

AUTOMATIC FEED-WATER REGULATOR FOR STEAM-BOILERS.

SPECIFICATION forming part of Letters Patent No. 269,512, dated December 26, 1882.

Application filed September 12, 1882. (No model.)

To all whom it may concern:

Be it known that I, JOHN CHRISTMAN, of Syracuse, in the county of Onondaga, in the State of New York, have invented new and useful Improvements in Automatic Feed-Water Regulators for Steam-Boilers, of which the following, taken in connection with the accompanying drawings, is a full, clear, and exact description.

10 This invention relates to a novel, simple, and effective device designed to automatically control the supply of water to steam-boilers; and it consists essentially in the control of the admission of steam to the feed-pump or injector by the rise and fall of the water in the boiler, all as hereinafter fully described, and specifically set forth in the claims.

Referring to the annexed drawings, Figure 1 is an elevation of my invention, illustrating 20 its connection with the boiler and with the pump which supplies the boiler with water. Fig. 2 is an enlarged vertical transverse section of my invention. Fig. 3 is a further enlarged horizontal section on line $x-x$ in Fig. 2, 25 and Fig. 4 is an enlarged detail view of the scraper or cleaner connected with the water-pipe of my automatic feed-water controller.

Similar letters of reference indicate corresponding parts.

30 B denotes a steam-boiler, which may be of any ordinary style and size, and P represents the pump which supplies the boiler with water.

A is a cylindrical chamber placed in a vertical position and relatively at the same elevation as the boiler, with which it communicates at its top and bottom by pipes a and b, tapping the boiler respectively above and below the standard water-line thereof, the water-connection between the cylinder A and boiler B being 35 effected by the aid of a stop-cock, n, interposed between the bottom of the chamber A and pipe b, so as to admit of excluding the water from said chamber when desired.

To prevent the clogging of the pipe b, I 45 apply to the interior of the end thereof which enters the boiler a perforated disk, h, as shown in Fig. 4 of the drawings. A manipulating-rod, m, is extended from the disk h longitudinally through the pipe b and through a stuffing-box on the outer end of said pipe, and is provided at its extremity with a suitable handle,

by means of which the disk h can be drawn through the pipe, and thereby caused to effectually clean the interior thereof, the inner end of the pipe b being provided with longitudinal slots l, through which the water enters said pipe. The top of the cylinder A is provided with a steam-eduction port or channel, c, arranged central of the axis of the cylinder, and from the port c is extended the steam-pipe D, 55 which supplies the motive power to the pump P, said pump having its discharge-pipe E extended to the water-space of the boiler and supplying said boiler with water.

F represents a float in the form of a light 65 hollow globe, which may be formed of thin sheet metal or other suitable material. To the bottom of this globe is attached a horizontal disk, f, which spans the cylinder A for the purpose hereinafter explained, and from the top 70 of the globe rises a valve-stem, e, which is in range with the eduction-port c, and terminates with a conical end fitted to a corresponding conical valve-seat, d, secured to the mouth of the eduction-port.

The chamber A, by its before-described communication with the steam and water spaces of the boiler B, becomes charged with steam and water and carries the same under pressure and on the same level as the contents of 80 the boiler. The float F, being buoyed on the surface of the water in the chamber A, is thus caused to rise and fall simultaneously with the rise and fall of the water in the boiler. The valve-seat d of the steam-eduction port is arranged at such an elevation and the valve-stem e of such length that when the water in the boiler approaches its maximum height the float F is caused to close the aforesaid eduction-port by forcing the valve-stem e into the 85 valve-seat d, thus shutting off steam from the pump P, and consequently stopping the operation of the same. Simultaneously with the fall of the water in the boiler the float, with its valve-stem e, recedes from the steam-eduction 90 port c and opens the same to admit steam to the pump P, thereby setting the same in operation to force water into the boiler.

It is to render more positive the fall of the float f, for which the disk f is attached to the 95 float, since the pressure of the steam is uniform on all sides of the globular float or radially

toward the center thereof, the action of said float depends solely on the weight thereof, and since the steam-eduction port is subject to suction, owing to the vacuum produced in the 5 actuating-cylinder of the pump by the sudden shutting off of steam, the aforesaid float is liable to be retained in its elevated position and caused to maintain the eduction-port closed after the water in the cylinder A has receded. 10 This I overcome by the medium of the disk f spanning the cylinder A, and receiving a direct vertical pressure from the water rising and falling in the cylinder, and thus compelling the float to follow the water more positively. 15 In order to admit of controlling the valve of the steam-eduction port at will of the engineer, and also prevent the float from dropping farther than necessary to open the aforesaid valve, I connect to the end of the valve-stem a rod, 20 r, which projects upward through the port or channel c and through a spider or skeleton diaphragm, S, which is seated on a shoulder or offset on the interior of the port c, as shown in Fig. 2 of the drawings. A collar or nut is secured to the rod r above the spider S in such 25 relative position as to arrest by its collision with said spider the descent of the float pendent from the rod r. Over the end of the rod r, and in range therewith, is a screw-threaded 30 push-rod, t, working in a screw-threaded stuffing-box, u, applied to the upper end of the port c.

Whenever it is desired to open the valve of the steam-eduction port c before the same is 35 effected by the fall of the water in the boiler in the manner before described, the push-rod can be turned to carry it down into the port c, and by its collision with the end of the rod r it forces the valve-stem away from the valve- 40 seat d, thus opening the eduction-port c.

It will be observed that my automatic feed-water controller is so organized as to effectually avoid friction and all other defects which might tend to impair its efficiency.

45 Having described my invention, what I claim

as new, and desire to secure by Letters Patent, is—

1. The combination, with an upright cylinder communicating with the steam and water spaces of a boiler and a float arranged within 50 said cylinder, of a horizontal disk suspended from the float and spanning the cylinder, substantially as and for the purpose specified.

2. An automatic feed-water controller for steam-boilers, consisting of an upright cylindrical chamber communicating with the steam and water spaces of the boiler, and having a steam-eduction port communicating with the actuating-cylinder of the feed-water pump, a float arranged to control the egress of steam 60 from said chamber, and a horizontal disk suspended from the float and spanning the chamber to receive a direct vertical water-pressure, and thereby overcome any suction that may be exerted on the float by the steam-eduction 65 port, substantially as set forth.

3. The combination, with the cylinder A, provided with the steam and water pipes a and b, of the steam-eduction port c, arranged central of the axis of the cylinder and provided 70 with the valve-seat d, and the float F, provided with the horizontal disk f, and the valve-stem e, projecting upward from the center of the float, substantially as shown and set forth.

4. The combination, with the cylinder A, 75 provided with the steam and water pipes a and b, and with the steam-eduction port c, and the float F, provided with the valve-stem e, as shown, of the push-rod t, substantially in the manner and for the purpose specified.

In testimony whereof I have hereunto signed my name and affixed my seal, in the presence of two attesting witnesses, at Syracuse, in the county of Onondaga, in the State of New York, this 9th day of September, 1882.

JOHN CHRISTMAN. [L. S.]

Witnesses:

Wm. C. RAYMOND,
F. H. GIBBS.
